UNITED STATES PATENT OFFICE.

JOHN E. DUNNIGAN, OF CLEVELAND, OHIO, ASSIGNOR TO CATHARINE DUNNIGAN, OF SAME PLACE.

OIL-CUP.

SPECIFICATION forming part of Letters Patent No. 373,059, dated November 15, 1887.

Application filed June 13, 1887. Serial No. 241,105. (No model.)

To all whom it may concern:

Be it known that I, JOHN E. DUNNIGAN, of Cleveland, in the county of Cuyahoga and State of Ohio, have invented certain new and useful Improvements in Oil-Cups, of which the following is a specification.

My invention relates to oil-cups for lubricating purposes; and it consists in the peculiar construction and combination of the several 10 parts, as hereinafter fully described, and pointed out in the claims.

In the accompanying drawings, Figure 1 is a side elevation of my new cup. Fig. 2 is a vertical section showing the plunger up, and 15 Fig. 3 is a vertical section showing the plunger down.

A is the base of the cup, provided with a hollow and externally screw-threaded neck, *a*, by which the cup may be secured to the portion of machinery to be lubricated.

B is the body or sides of the cup, having its ends screw-threaded, and is fixed in the flange of the base A.

C is a crown-shaped cap or cover which 25 screws onto the top of the body and has a central opening, *c*.

D is a central stand-pipe secured in the base A, with its bore in direct line with the bore in the neck *a*. The upper half of said stand-pipe 30 has straight parallel sides. From thence the outside to near the bottom is gradually reduced in size by being tapered downward, for a purpose hereinafter shown.

E is a chambered piston-rod playing through 35 the cover C, is screw-threaded on its outside, but does not turn therein. F is a thumb-nut playing on the said rod E, and is provided with a spring-latch, consisting of a bent spring-wire, G, fixed in a slot in the nut, and catches 40 into a notch, *e*, in the upper corner of the rod E.

H is a piston consisting of a disk, H, having an internally and externally screw-threaded neck, *h*, by which it is secured to the end of the rod E. A packing-ring, of leather or other 45 suitable material, I, is secured to disk H by means of a second disk, J, screwed onto the neck *h* of disk H. The edge of the ring is shaved off thin and is turned down over the edge of disk H, and thus forms a close joint.

50 In the lower open end of the rod E is fixed a

bushing-ring, K, whose inner diameter is but a little greater than the diameter of the upper end of the stand-pipe D.

L is a convolute spring bearing upon the piston H and against the under side of the 55 cover C and surrounds the rod E.

M is a regulating and cut-off gate, consisting of a partly screw-threaded pin placed in a transverse bore in the base A, having a tapering pointed end fitting in a tapering recess 60 transverse to the bore in neck *a*. In the head of said pin M a bent spring-wire latch, N, is fixed, whose free end is inserted in one of the holes *x* in the side of the base A. By means of this latch the pin may be set at any 65 required point for regulating the quantity of oil to be fed through the neck.

The working of this cup is as follows: The cup being filled with oil, which occupies the space between the piston and the base, now, 70 by the pressure of the spring upon the piston, the oil is forced upward into the chamber in the rod E. It thence drops down the stand-pipe and through the neck *a*. The purpose of the taper of the stand-pipe is, as the piston 75 descends and the tension of the spring decreases the open space in the bottom of the chambered rod may be increased in area around the stand-pipe to give greater freedom for the ingress of oil.

The purpose of the thumb-nut F is for withdrawing the piston when the cup has become exhausted and requires refilling. This is done by turning the nut, which bears against the cover and draws the rod outward, compressing 85 the spring. Then the cover may be removed, together with the piston, by unscrewing it, leaving the cup open. Then the cup is filled with oil and the cover is again screwed on. The piston now bears upon the oil. The 90 nut F is then turned up to the top end of the rod E. The latch catches in the notch, retains the nut, and prevents its being run down by jarring or otherwise. The gradual inward movement of the piston-rod shows the progress 95 of the feeding of the cup, and when the rod has passed clear in and the nut rests on the cover, shows that the cup is empty.

Having described my invention, I claim—

1. In combination, an oil-cup having a dis-

100

charge-opening in its bottom, a central stand-pipe having tapering sides, and a piston having a screw-threaded and chambered rod playing through the cover and down over the said stand-pipe, and a nut on said rod, as and for the purpose specified.

2. In combination, an oil-cup having a discharge-opening in its bottom, a central stand-pipe, a piston having a screw-threaded and chambered rod playing through the cover and down over said stand-pipe, a thumb-nut having a latch mechanism above the cover, and a spring bearing on the piston, constructed and operating substantially as and for the purpose specified.

3. The combination, in an oil-cup having a discharge-opening in its bottom, of a central stand-pipe, a piston consisting of a disk, H, having a screw-threaded neck, h, a packing-ring, I, held by disk J, screwed onto said neck 20 h, and said disk screwed onto end of chambered rod E, which plays through the cover of the cup, and both the piston and chambered rod playing down over the said stand-pipe, constructed and operating substantially in the 25 manner and for the purpose specified.

JOHN E. DUNNIGAN.
